UNITED STATES PATENT OFFICE

96,652

DESIGN FOR A MASK FOR A TYPEWRITING MACHINE

Bernard J. Dowd and Henry J. Hart, West Hartford, Conn., assignors to Royal Typewriter Company, Inc., New York, N. Y., a corporation of New York

Application May 18, 1935, Serial No. 56,903

Term of patent 14 years

To all whom it may concern:

Be it known that we, Bernard J. Dowd and Henry J. Hart, citizens of the United States, residing at West Hartford, in the county of Hartford, State of Connecticut, have invented a new, original, and ornamental Design for a Mask for a Typewriting Machine, of which the following is a specification, reference being had to the accompanying drawing, forming part thereof.

In the accompanying drawing, the figure is a perspective view of a mask for a typewriting machine showing our design, both sides of the mask being substantially alike.

We claim:

The ornamental design for a mask for a typewriting machine substantially as shown and described.

In testimony whereof, we have hereunto subscribed our names.

BERNARD J. DOWD.
HENRY J. HART.
